ISAAC B. WENTWORTH, OF NEW YORK, N. Y.

Design No. 4,356, dated September 13, 1870.

DESIGN FOR A HAT.

The Schedule referred to in these Letters Patent and making part of the same.

To all whom it may concern:

Be it known that I, ISAAC B. WENTWORTH, of the city of New York, in the county and State of New York, have invented a new and original Design for Hats; and I do hereby declare that the following is a full, clear, and exact description thereof, which will enable others skilled in the art to make and use the same, reference being had to the accompanying drawing forming part of this specification.

The nature of my invention is fully represented in the accompanying drawing, to which reference is made.

I claim as my invention—

The improved design for hats, substantially as herein shown.

The above specification of my invention signed by me this 22d day of August, 1870.

ISAAC B. WENTWORTH.
